UNITED STATES PATENT OFFICE

FREDERICK W. ENGEL, OF ELMHURST, NEW YORK, ASSIGNOR TO ENGEL BROTHERS, INC., OF NEW YORK, N. Y., A CORPORATION OF NEW YORK

BRACELET

Application filed May 14, 1930. Serial No. 452,225.

This invention relates to bracelets, and more particularly to bracelets of the link type.

Among the principal objects which the invention has in view are:—To provide a bracelet wherein the jewel mounting is obtained at those parts of the bracelet which appear in use as the hinge connections between links; to obtain a structure wherein the jewel may be mounted at a part of the bracelet which heretofore has been a weak spot without danger of losing the jewel; to thus provide a very secure mounting for the jewel at a part of the bracelet at which it has been unsafe to mount jewels heretofore; to maintain the usual formation of transverse link structure with the links actually in a common plane; to obtain increased rigidity between the parts; to prevent lateral sagging of the bracelet; to secure simplicity of construction and neatness of appearance; and to obtain other advantages and results as may be brought out in the following description.

25 In the drawings:—

Figure 1 is a plan of a bracelet stretched out in open position embodying my invention:

Figure 2 is an elevation and sectional view 30 as taken on line 2—2 of Figure 1;

Figure 3 is a cross sectional view taken on line 3—3 of Figure 1;

Figure 4 is a side elevation of a bracelet member on a larger scale than shown in Figure 2; and

Figure 5 is a bottom plan of the bracelet member shown in Figure 4.

Description:

In the specific embodiment of the invention illustrated in said drawings, it is pointed out that the bracelet is formed to represent a plurality of links 6, 6 substantially in a common plane and with connecting or up-standing links 7, 7 therebetween in a plane transverse to the plane of the first said links

6, 6. In the present showing, the links 6, 6 are themselves made in sections; that is, comprise a pair of end portions 8, 8 which are hinged together by means of overlapping ears 9, 9 at the middle of the link 6. The upstanding links 7, 7 instead of being movable with respect to links 6, 6 connected thereto as heretofore, are rigid and preferably an integral part with the contiguous portions of adjacent links 6, 6. That is to say, adjacent portions 6, 6 of a pair of links are formed integrally or otherwise rigid with respect to the connecting transverse links 7, and for the sake of convenience, these integrally formed parts will be referred to as a bracelet member 10. One of these bracelet members 10 is shown separately in Figures 4 and 5. It will be clear by inspection of those figures that said member provides oppositely directed halves of two adjacent links, the outer ends of which provide ears 9, 9 enabling other similar members to be pivotally attached thereto. The transverse link 7 connecting these two halves of links 6, 6 is integral with the two halves as clearly shown in Figure 3, and therefore, provides a strong jewel mounting having no directly connected movable parts which tend to cause a jewel to become loose and be ultimately lost.

It will be understood that the several members 10 are combined in series to form a bracelet, and special clamp members 11 and 12 are employed at the opposite ends of the series enabling the bracelet to be secured together at its ends. The fact that the links 6, 6 are hinged at their middle parts enables the bracelet to be curved around the user's wrist and secured by means of the clasp members notwithstanding the fact that the transverse links are formed integral with the end portions of the outer links.

It is to be understood that other specific designs of links can be employed than the exact one illustrated herein, and other detail

modification and changes can be made in the construction and use of my invention.

Claims:

1. A bracelet comprising in combination a plurality of links alternately disposed transversely with respect to each other, adjacent portions of alternate links being rigid with respect to the connecting links.
2. A bracelet comprising in combination a plurality of links alternately disposed transversely with respect to each other, adjacent portions of alternate links being rigid with respect to the connecting links, said adjacent portions of alternate links being hinged with respect to other portions of said links.
